(57) **CLAIM**

The ornamental design for a rack-mountable display, as shown and described.

DESCRIPTION

FIG. 1 is a front elevational view of a first embodiment of a rack-mountable display showing our new design;

FIG. 2 is a rear elevational view thereof;

FIG. 3 is a top plan view thereof;

FIG. 4 is a bottom plan view thereof;

FIG. 5 is a right side elevational view thereof;

FIG. 6 is a left side elevation view thereof;

FIG. 7 is a top, front, and left side perspective view thereof;

FIG. 8 is a front elevational view of a second embodiment of a rack-mountable display showing our new design;

FIG. 9 is a rear elevational view thereof;

FIG. 10 is a top plan view thereof;

FIG. 11 is a bottom plan view thereof;

FIG. 12 is a right side elevational view thereof;

FIG. 13 is a left side elevation view thereof; and,

FIG. 14 is an exploded top, front, and left side perspective view thereof.
